(57) **CLAIM**

The ornamental design for a seat with desk, as shown and described.

DESCRIPTION

FIG. 1 is a front perspective view of the seat with desk of the present invention;

FIG. 2 is a front elevation view thereof;

FIG. 3 is a rear elevation view thereof;

FIG. 4 is a left side elevation view thereof, the right side elevation being a mirror image thereof;

FIG. 5 is a top plan view thereof;

FIG. 6 is a bottom plan view thereof;

FIG. 7 is a front perspective view of a second embodiment of the seat with desk of the present invention;

FIG. 8 is a front elevation view thereof;

FIG. 9 is a rear elevation view thereof;

FIG. 10 is a left side elevation view thereof, the right side elevation being a mirror image thereof;

FIG. 11 is a top plan view thereof; and,

FIG. 12 is a bottom plan view thereof.

Any features illustrated in broken lines do not comprise part of the presently claimed design.
